BAND BODY FOR ORNAMENTAL AND
PRACTICAL PURPOSESHeinrich Bürk, Pforzheim-Brotzingen, Germany,
assignor to the firm Ph. Döppenschmitt, Gold-
warenfabrik, Pforzheim, GermanyApplication June 2, 1937, Serial No. 146,101
In Germany July 10, 1936

7 Claims.

(Cl. 63—3)

The invention relates to a link bracelet, the links of which consist of juxtaposed plates.

Link bands of this type are known. The plate-shaped links of sheet metal are juxtaposed by means of bent-over edges at both ends engaging over the end edges of a band-shaped carrier. As carrier for the links, wire fabric or wire plaiting, particularly strips of plaiting of wire spirals are used.

10 These known bands have the inconvenience that the bent-over edges of the plate-shaped links engage over the rear side of the carrier, which not only impair the appearance of the structure of the plaiting, but is a hindrance when 15 the band is used in so far as hairs of the skin can be clamped as well in the joints between the individual bent-over edges of the plates as also in the joints between the end edges of the bent-over ends.

20 By the invention an absolutely uniform rear side of the band is attained, which no longer shows the above mentioned inconveniences.

The novelty consists therein that the ends of the plate-shaped links are first bent over towards the rear and these parts engage under the outwardly directed portions of the two folded edges bent on the carrier of wire plaiting or wire fabric.

In this manner no bent over ends of the plates are lying on the rear side of the band. Any contact of plate parts with the skin is avoided. On the skin is lying only the porous wire plaiting or wire fabric which, as is known, is permeable in a high degree for exhalations of the skin.

25 For the production of the edges of the band the dimensions of the plates may be selected so that after their ends have been bent in accordance with the invention, they still laterally project over the edges of the plated band.

The protection of the latter and the fixation 40 of the plates on the strip of plating may be further improved thereby that by bending down the inwardly folded-over parts of the plates, the edges of the plated band are covered at the sides.

Three embodiments of the invention are shown, 45 by way of example, in the accompanying drawing of which:—

Fig. 1 is a top plan view.

Fig. 2 a side elevation and

Fig. 3 a cross section on a larger scale of the 50 first embodiment of the invention.

Fig. 4 shows in top plan view, and

Fig. 5 in cross section on enlarged scale the 55 second embodiment of the invention.

Fig. 6 is a cross section on enlarged scale of the third embodiment of the invention.

Figs. 7 and 8 show in elevation two link plates set off in different manner before they are folded over.

The edges *a* and *b* of the strip *c* of plaiting, serving as link carrier are bent over in inward direction and form in this manner folded edges. The plate-shaped links *e* which, for increasing the pliability and flexibility of such a band body, are measured in the direction of the band length preferably smaller than measured in the direction of the band width, show at each of their ends an inwardly bent over part *f* and an outwardly folded-over part *d*. The latter parts engage under the folded edges *a* and *b* bent on the carrier *c* of wire plaiting or fabric. In this manner 15 a durable fixation of the plates *e* on the carrier *c* is effected.

The durability of the band body may still be further increased thereby that the parts *f* folded over inwards, slightly project over the longitudinal edges of the carrier strip *c*, as shown in Fig. 5. In order to then grip the edges *a* and *b* especially strongly between the parts *f* and *d*, the projecting parts *f* may be slightly bent downwards. At corresponding side of the projecting part *f*, it can as shown in Fig. 6 cover the longitudinal edges of the band *c* of wire plaiting or fabric, so that these edges are no longer visible and besides ensured against damaging.

It has been found that in consideration of the durable construction of the band body the thickness of the carrier *c* of fabric or plaiting as well as that of the plates *e* can be very little. The hollow space *h* produced between *c* and *e* in consequence of the mutual edge-folding of the parts, is thereby comparatively smaller in the final rolled band body than that illustrated in the drawing, which is drawn on larger scale. If the plates have to be plane the hollow space *h* is filled by an insert *g* which may consist also of a strip of plaiting or fabric or of any other suitable band-shaped body.

If as insert *g* one or several blade springs are selected which have the tendency to roll up, the band body constructed as bracelet will automatically hold on the arm owing to its resiliency.

The ends of the plate links *e* are preferably set off on one or both sides measured in the direction of the band length on the parts *f* and *d* situated in the folded portion, as is shown in Figs. 7 and 8 so that the edges of the plate at these points do not strike the one on the other when the band body is being curved.

The plates may be ornamented as desired.

I claim:

1. A band body for ornamental and useful purposes, consisting of a band-shaped carrier and of plate-shaped links fixed on this carrier, the ends of the links being first bent-over inwards towards the rear side and then bent-over outwards and thence outwardly bent portions engaging under folded-over edges of said carrier.
2. A band body as specified in claim 1, in which the inwardly bent-over portions project laterally over the longitudinal edges of the link carrier.
3. A band body as specified in claim 1, in which the inwardly bent-over portions project laterally over the longitudinal edges of the link carrier and are curved downwards so that they partly cover the longitudinal edges of the link carrier.
4. A band body as specified in claim 1, in which the inwardly bent-over portions project laterally over the longitudinal edges of the link carrier and

are curved downwards so that they completely cover the longitudinal edges of the link carrier.

5. A band body as specified in claim 1, comprising in combination with the link carrier plate shaped links, the folded-over edges of which engage the one over the other so that a hollow space is formed and an insert in said hollow space.

6. A band-body as specified in claim 1, comprising in combination plate shaped links the parts of which folded over inwards and outwards are set off on one side in the direction of the band length.

7. A band body as specified in claim 1, comprising in combination plate shaped links the parts of which folded over inwards and outwards are set off on both sides in the direction of the band length.

HEINRICH BÜRK.
